CATHODE RAY TUBE DEFLECTING
DEVICE

Ioury G. Maloff, Philadelphia, Pa., assignor to
Radio Corporation of America, a corporation
of Delaware

Application October 31, 1935, Serial No. 47,556

7 Claims. (Cl. 250—157)

My invention relates to deflecting means for cathode ray tubes and particularly to electro-magnetic deflecting means.

In the past, electro-magnetic deflection has involved two disadvantages; it caused a certain amount of defocusing of the cathode ray, and it caused the cathode ray to scan on the screen in an area which had curved sides rather than straight sides.

10 An object of my invention is to provide electro-magnetic deflecting means which avoids, to a marked extent, the above mentioned disadvantages.

15 A further object of my invention is to provide a simplified deflecting structure which is cheap to manufacture.

20 In practicing my invention I provide a magnetic core structure which may be either rectangular or round in shape. Deflection in one plane, vertical deflection for example, is accomplished by means of two coils wound on opposite sides of the core and so electrically connected that their magnetic fields buck. Another pair of coils, also connected to produce bucking fields, 25 may be mounted on the core for deflecting the cathode ray vertically.

25 Other objects, features and advantages of my invention will appear from the following description taken in connection with the accompanying drawing in which,

30 Figure 1 is a view in perspective of deflecting coil structure embodying my invention.

Fig. 2 is a view illustrating the structure shown in Fig. 1 applied to a well known form of cathode ray tube, and

35 Figs. 3 and 4 are views illustrating other embodiments of my invention.

40 Referring to Fig. 1 this embodiment of my invention comprises a closed magnetic core structure 1 which is rectangular in shape. The core preferably is built up of laminations of transformer iron. Deflecting coils 2 and 3 for producing horizontal deflection of a cathode ray are mounted on the vertical legs 4 and 6 of the core. 45 These coils are so connected either in series or in parallel that the magnetic fields produced by the two coils are in bucking relation as indicated by the letters N and S on the drawing.

45 It will be seen that the lines of force leave the upper horizontal leg 7 of the core and pass into the lower horizontal leg 8 of the core as indicated by the dotted lines.

50 The position of the cathode ray tube is indicated at 9 by the dotted circle. It will be apparent that in the region of the cathode ray tube

5 the strength of the magnetic deflecting field is fairly uniform whereby there is a reduction in defocusing of the cathode ray and in distortion 10 of the scanning pattern. The uniformity of the magnetic field may be improved by providing 5 projections 11 and 12 on the horizontal legs 7 and 8, respectively, as illustrated in Fig. 1. It should be understood, however, that such projections 15 are not necessary for satisfactory operation of the deflecting system. It may be noted that for best operation the deflecting coils 2 and 3 are of 20 substantially the same length as the vertical legs of the core, that is, they should take up substantially all the space available for deflecting coils.

25 Referring to Fig. 2, the deflecting coil structure 15 described above is shown applied to a cathode ray tube 9 of the type employing electrostatic focusing of the cathode ray. The cathode ray tube is of a well known type comprising a highly evacuated envelope having therein an indirectly 20 heated cathode 13, a control grid 14, a first anode 16 and a second anode 17. The second anode 17 consists of a metallic coating on the inner surface of the envelope and it functions both to accelerate the electrons and to focus them to a 25 small spot on a fluorescent screen 18 at the end of the tube.

30 When a deflecting coil structure such as shown in Fig. 1 is employed, if it is desired to deflect a cathode ray in a direction at right angles to the 35 deflection produced by the deflecting coils, such deflection is preferably produced by electrostatic deflecting plates. It is sometimes preferred however, to obtain both vertical and horizontal deflection by means of deflecting coils. In that 40 case the embodiment of my invention illustrated in Fig. 3 may be employed. This structure is substantially the same as that shown in Fig. 1 except that vertical deflecting coils 19 and 21 have been mounted on the horizontal legs of a core 22. 45 The horizontal deflecting coils 23 and 24 are so connected either in series or in parallel that their magnetic fields are in bucking relation as indicated by the letters N and S. Thus the vertical deflecting coils 19 and 21 produce a north pole 45 at the left hand vertical leg of the core and a south pole at the right hand vertical leg of the core.

50 The horizontal deflecting coils 23 and 24 are likewise so connected that their magnetic fields 50 buck to produce a north pole in the upper horizontal leg of the core and a south pole at the lower horizontal leg of the core. It will be understood, of course, that the north and south poles reverse their locations with the reversal of 55

current through the deflecting coils. As mentioned in connection with Fig. 1, the deflecting coils preferably occupy all the available space on the core legs. In order to illustrate the invention more clearly, considerable unused space on the core legs has been shown in Fig. 3.

It will be apparent that the sensitivity of the deflecting system shown in Fig. 3 is reduced by the fact that it is impossible to bring the legs 10 of the core 22 close to the envelope of the cathode ray tube 9 due to the windings being located between the core and the envelope. This defect is largely overcome and the magnetic field is made still more uniform by employing the arrangement shown in Fig. 4. In this embodiment of the invention each coil on a core leg is split and spaced apart whereby a projection may be provided on the leg between the two coil sections. The two coil sections are connected in series and 15 the two series connected sections then connected with the remaining coils the same as in the embodiment illustrated in Fig. 3. For example, considering the horizontal deflecting coils, the right hand vertical leg 26 of the core has two coil sections 27 and 28 connected in series and spaced apart, there being a projection 29 on the portion of the core leg which is between the coil sections. The two coil sections 27 and 28 on the right hand vertical leg are connected in bucking relation with 20 the two coil sections 31 and 32 located on the left hand vertical leg 33. It will be understood that the two coil sections on a core leg may be connected either in series or in parallel so long as their magnetic fields are in a direction to aid 25 each other.

On the upper horizontal core leg 34, the two vertical deflecting coil sections 36 and 37 are connected with their fields in aiding relation while on the lower horizontal core leg 38 the 30 vertical deflecting coil sections 39 and 41 are likewise connected with their magnetic fields in aiding relation. The connection of the vertical deflecting coils on the upper horizontal leg with respect to the vertical deflecting coils on the lower horizontal leg is such that the magnetic fields from the two horizontal legs 34 and 38 buck each other to form north and south poles on the vertical legs 26 and 33 as indicated by the letters N and S.

50 In addition to the increased sensitivity obtained by splitting the deflecting coils and providing core projections as illustrated in Fig. 4, there is a further advantage in this particular structure in that it provides a still more uniform magnetic field in the region of the cathode ray tube 9 both because of the core projections and because of the fact that the deflecting coils are split and spaced apart.

It will be evident that in addition to providing 60 a deflecting structure which gives improved results I have provided a structure which is very simple in construction and which can be manufactured cheaply in quantity production.

From the foregoing description it will be apparent 65 that various modifications may be made in my invention without departing from the spirit and scope thereof and I desire, therefore, that only such limitations shall be imposed thereon as are necessitated by the prior art and are set forth in the appended claims.

I claim as my invention:

1. In combination, a cathode ray tube, electro- 70 magnetic deflecting means for deflecting the cathode ray in said tube, said means comprising a closed magnetic core structure having a first

pair of oppositely disposed legs and a second pair of oppositely disposed legs, a pair of deflecting coils wound on said first pair of core legs, said coils being connected with their magnetic fields in bucking relation to produce a deflecting field in the area surrounded by said core and with the deflecting field leaving one leg of said second pair and entering the other leg of said second pair, said second pair of core legs having opposing faces of such contour as to produce a substantially uniform field in the region of the cathode ray being deflected, said core structure being so positioned that said deflecting field is substantially transverse to said cathode ray. 5

2. In combination, a cathode ray tube, electro- 15 magnetic deflecting means for deflecting the cathode ray in said tube, said means comprising a closed magnetic core of rectangular shape, said core having two similar vertical legs and two similar horizontal legs, a pair of similar deflecting coils wound upon one pair of said similar legs and connected with their magnetic fields in bucking relation whereby a deflecting field is produced which is symmetrical with respect to the center of said core, the other pair of said similar legs having opposing faces which are free of projections of sufficient length to concentrate the deflecting field in the region of the cathode ray being deflected whereby a substantially uniform field is produced in said region, said core structure being so positioned that said deflecting field is substantially transverse to said cathode ray. 20

3. In combination, a cathode ray tube, electro- 25 magnetic deflecting means for deflecting the cathode ray in said tube, said means comprising a closed magnetic core structure of rectangular shape, said core structure having two similar vertical legs and two similar horizontal legs, a pair of similar deflecting coils wound upon a pair of said similar legs and connected with their 30 magnetic fields in bucking relation whereby a deflecting field is produced which is symmetrical with respect to the center of said core, said core structure being so positioned that said deflecting field is substantially transverse to said cathode ray. 35

4. In combination, a cathode ray tube, electro- 40 magnetic deflecting means for deflecting the cathode ray in said tube, said means comprising a closed magnetic core structure of rectangular shape, said core structure having two similar vertical legs and two similar horizontal legs, a pair of similar deflecting coils wound upon a pair of said similar legs and connected with their 45 magnetic fields in bucking relation whereby a deflecting field is produced which is symmetrical with respect to the center of said core, said core structure being so positioned that said deflecting field is substantially transverse to said cathode ray, and a second pair of similar deflecting coils wound upon the other pair of said similar legs and connected with the magnetic field of said second pair of coils in bucking relation. 50

5. Electro-magnetic deflecting means for a cathode ray tube, said means comprising a closed magnetic core structure, a pair of vertical de- 55 flecting coils wound on opposite sides of said core and connected with their magnetic fields in bucking relation, and a pair of horizontal deflecting coils wound on opposite sides of said core and connected with their magnetic fields in bucking 60 65 70 75 75

relation, said two pairs of coils being so positioned with respect to each other that the deflecting field of one pair of coils is substantially at right angles to the deflecting field of the other pair of coils.

5 6. The invention according to claim 5 characterized in that each of said coils is split into a plurality of sections which are spaced apart.

7. The invention according to claim 5 charac-

terized in that each of said coils is split into a plurality of sections which are spaced apart, and further characterized in that projections extend from the core portions between said coil sections towards the center of said core structure, said 5 projections being arranged symmetrically with respect to said center.

IOURY G. MALOFF.
